UNITED STATES PATENT OFFICE.

NATHANIEL DAVIS, OF MONTPELIER, VERMONT, ASSIGNOR TO GEORGE L. DAVIS, OF NORTH ANDOVER, MASSACHUSETTS.

WATER-COOLER.

SPECIFICATION forming part of Letters Patent No. 398,770, dated February 26, 1889.

Application filed August 13, 1888. Serial No. 282,566. (No model.)

To all whom it may concern:

Be it known that I, NATHANIEL DAVIS, of Montpelier, county of Washington, State of Vermont, have invented an Improvement in 5 Water-Coolers, of which the following description, in connection with the accompanying drawings, is a specification, like letters and figures on the drawings representing like parts.

This invention has for its object the production of a water-cooler which is effective 10 with but little ice.

In accordance with my invention I provide a box within which I place a stone jar having above its cover an ice-chamber, the said jar having a faucet by which to draw from it the cold water. I have also shown the jar as being capable of being filled without removing the cover. To facilitate the cooling action of the descending cold air and the water from 20 the melted ice, I have provided the jar at its exterior with spiral grooves or troughs in which the air and water are caught and made to rest, so as to gradually reach the bottom of the jar.

25 My invention in a cooler consists in the combination, with a surrounding jacket or case and a covered jar, of an ice-receptacle located immediately above in contact with the cover or top of the jar, and a faucet or outlet leading from the jar out through the jacket or case.

Other features of my invention will be herein described, and pointed out in the claims at the end of this specification.

35 Figure 1 is a vertical section of a water or liquid cooler embodying my invention, and Fig. 2 a view of the jar removed.

The jacket or casing A is herein shown as having double walls, as a a', sufficiently removed from each end to leave air-chambers, which are subdivided by partitions b, preferably of paper or some other thin cheap material, treated with paraffine or other equivalent substance to render the partition substantially water-repellent and air-proof. The lid 40

45 B of the jacket or casing, hinged at 2, is also shown as made in like manner to leave air-chambers therein. The bottom of the jacket is provided with a water-outlet, as b', which is 50 closed by a screw-plug, b'.

Within the jacket I have placed a vertical

wall, c, which terminates short of the inner bottom of the jacket, so as to leave an air-passage, 3, the interior of the jacket between the division-wall c and one side of the jacket 55 having a horizontal shelf, as c', which, as shown, serves to support the ice-chamber d, which will preferably be of metal flanged over at its top to form a lip, 4, and contracted at its lower end to come close to the cover e of 60 the jar f of stone or other usual material, the cover forming the bottom thereof.

The jar f is provided at its outer side with ribs or channels 6, preferably extended about the jar, as best shown in Fig. 2, so that the 65 water from the melting ice in the chamber d, as it passes from the cover, will follow down over the body of the jar, slowly running around and around the jar, and, further, the cold air in the chamber or space between the 70 jar and the partition c and the inner wall, d, as it descends is made to settle more slowly by reason of the channels 6.

Any air at the bottom of the jar which is sufficiently light or warm to rise has opportunity to do so in the space g, and to enter 75 the ice-chamber.

The cold water in the jar f may be drawn out through the outlet-pipe or faucet h.

The water to be cooled may be introduced 80 into the jar by an inlet-pipe, as m, extended through the ice-chamber and into the cover e.

The apparatus herein shown forms a most excellent water or liquid cooler, which is very efficient in operation, and may be run with 85 but a small amount of ice.

Although I prefer to make the jacket or casing as shown, yet it may be made as are the walls of any usual refrigerator-box without departing from my invention.

90 Preferably the jar will be made as shown, yet the channels 6 might be omitted, and such a jar combined with the cover and ice-chamber and jacket would produce a very good water-cooler.

I claim—

1. The jacket or casing and the jar f and its outlet h, extended through the jacket or casing, combined with the cover e, for the jar, and the ice-chamber d, located immediately 100 above the said cover, the cover forming the bottom of the ice-chamber, and an inlet-pipe

for the said jar extended through the ice-chamber, substantially as shown and described.

2. The jacket or casing having the walls 5 subdivided as described, and having the inner partition, *c*, terminating above the bottom of said jacket to form an air-passage, combined with the jar, its outlet *h*, the cover, the ice-chamber immediately above and in close 10 contact with it, and an inlet-pipe passing

through the ice-chamber into the jar, substantially as described.

In testimony whereof I have signed my name to this specification in the presence of two subscribing witnesses.

NATHANIEL DAVIS.

Witnesses:

G. W. GREGORY,
B. DEWAR.

It is hereby certified that Letters Patent No. 398,770, granted February 26, 1889, upon the application of Nathaniel Davis, of Montpelier, Vermont, for an improvement in "Water Coolers," was erroneously issued to George L. Davis as sole owner of the patent; that said Letters Patent should have been issued to said *Nathaniel Davis and George L. Davis*, jointly, said George L. Davis being assignee of one-half interest only as shown by the record of assignments in this Office; and that the proper correction has been made in the files and records of the case in the Patent Office, and should be read in the Letters Patent that the same may conform thereto.

Signed, countersigned, and sealed this 12th day of March, A. D. 1889.

[SEAL.]

D. L. HAWKINS,
Assistant Secretary of the Interior.

Countersigned:

BENTON J. HALL,

Commissioner of Patents.
